UNITED STATES PATENT OFFICE.

ERNEST WILLIAM BLAKE, OF LONDON, ENGLAND.

SURGICAL BANDAGE.

Application filed June 11, 1926, Serial No. 115,184, and in Great Britain September 15, 1925.

This invention relates to surgical bandages and has for its object to provide an improved form of bandage fastening which can be readily secured in any desired position without the aid of pins, clips or the like and in which the fastening means employed will not become adherent to the bandage proper or to any part of the body on which the bandage is used.

According to the invention improved means for fastening a surgical bandage in position are provided comprising a tape or the like threaded through a slot or slots in one end of the bandage and secured in place by causing its end to adhere to its main portion, the said tape or the like being of a known character and such that it will instantly adhere to itself but will not adhere to the bandage or to any portion of the body on which the bandage is used.

Reference will now be made to the accompanying drawings which illustrate by way of example a construction according to the invention and in which:—

Figure 1 is a front elevation showing one end of a bandage with fastening means attached and

Figure 2 is a vertical section taken on the line 2—2 of Figure 1.

In the drawings *a* indicates one end of a surgical bandage which may be of any desired kind, this end portion of the bandage being formed with three slits *b*, *c* and *d*. The fastening means comprises a tape *e*, the face *e'* of which is of such a character that one portion of the tape will instantly adhere to another portion thereof but will not adhere to the bandage or to the skin of the user. The tape *e* is attached to the bandage *a* by threading it successively through the slits *b*, *c* and *d* in the directions shown in

Figure 2, the end *f* of the tape being then bent upwardly into engagement with the main portion of the tape to which the end adheres at the points *g* and *h*, the connection at *g* preventing any relative movement between the bandage *a* and the looped end of the tape which may tend to loosen the completed bandage or to form creases therein.

In use, a bandage arranged as above described is placed in position around the part of the body to be treated, such part being encircled by the tape *e*, the end of which can be secured to the main portion of the tape at the exact point required to make a tight bandage by simply pressing the two portions of tape together. Alternatively, each end of a bandage may be provided with tapes arranged as above described and as shown and the free ends of such tapes caused to adhere to maintain the bandage in place. The invention is not limited, however, to the particular shape of bandage shown in the drawings and any number of straps may be employed attached to the sides or corners of the bandage in accordance with the requirements of particular cases. Furthermore, the member *e* may be constituted by any suitable flexible tape, cord or strapping which is capable of being rendered self-adherent.

I claim:—

Means for fastening a surgical bandage in position, comprising in combination a bandage formed with three slits, a self adhesive tape threaded through the slits and bent back on itself so that the two portions when pressed together become mutually adherent between the outer and middle slits and beyond the end of the bandage.

In witness whereof I affix my signature.

ERNEST WILLIAM BLAKE.
